UNITED STATES PATENT OFFICE.

WALLACE W. LYON AND JAMES L. DAVIS, OF MOUNT SALEM, KENTUCKY;
SAID DAVIS ASSIGNOR TO RICHARD M. STEWART, OF ATLANTA, GEORGIA.

CRUPPER.

SPECIFICATION forming part of Letters Patent No. 739,195, dated September 15, 1903.

Application filed January 3, 1903. Serial No. 137,658. (No model.)

To all whom it may concern:

Be it known that we, WALLACE W. LYON and JAMES L. DAVIS, of Mount Salem, in the county of Lincoln and State of Kentucky, have invented a new and useful Improvement 5 in Cruppers, of which the following is a specification.

Our invention relates to an improvement in that class of cruppers for harness in which 10 the tail of the horse is supported and held in correct position, its object being to so support the tail as to add to the general appearance of the horse and at the same time prevent the tail from hanging to one side and maintain 15 it in a central position.

Our invention consists in certain novel features of construction, arrangement, and combination of parts, as will be hereinafter fully described, and pointed out in the claims.

20 In the drawings, Figure 1 is a perspective view of the crupper. Fig. 2 is a detail view with the tail-support removed and partly in section. Fig. 3 is a longitudinal sectional view. Fig. 4 is a transverse sectional view.

25 Fig. 5 is an end view of one end of the tail-support. Fig. 6 is a detail perspective view of the front end of the frame.

In carrying out our invention we use a frame A of the shape shown and comprising 30 the metallic side bars or rods a a, the flattened apex portion a', and the separated rear ends a² a², curved inwardly toward each other and also downwardly, so as to fit on the buttocks of the horse. This frame is covered 35 with leather, the flattened end portion extending under a slot b, made in the back-strap B, the purpose of which will be explained hereinafter. The curved ends a² a² of the frame are threaded, as at D, inwardly a suitable 40 distance, the threads on one end being right-hand threads and the threads on the opposite end being left-hand threads.

Rigidly secured to or integral with each side bar or rod a a, just in the rear of the 45 threaded portions, are the collars C C, one face of which is provided with serrations or ratchets c, and the other face of each collar being smooth, as at c', and inclosed within the leather cover L of the crupper. Preferably 50 the opposing face of the collars C are provided with serrations or ratchets.

A right and left threaded nut or turnbuckle E is fitted to the threaded ends D of the rods B and provided with a row of holes or sockets F to receive a pin or nail to turn 55 the same when it is desired to draw the ends of said rods B B toward each other or move them farther apart.

The collars C C, fitting in a seat in the ends of the leather covering L, form a shoulder l, 60 against which the ends of the cylindrical sleeve member H of the tail-support abut. This portion H of the tail-support consists of a hollow metal cylinder having secured within its ends a suitable distance, the disks 6; I I, provided with the central apertures to freely admit the ends of rods B. The outer faces of said disks are serrated or provided with ratchets i i, the teeth, however, pointing in opposite directions to those on the collars C C. 70 The sleeve H is also provided with a slot J in one side, preferably the under side, through which a pin or nail is to be inserted when necessary to adjust the device by turning the nut E. Extending upwardly and rearwardly 75 on a suitable curve from the sleeve H, to which it is rigidly attached and forms a part of, is the tail-support K, being made of sheet-steel or other suitable thin metal and concaved transversely, as clearly shown. At suitable 80 points, preferably at about the center and near the free end of said support K, we attach straps or springs M, to pass around the bone of the tail.

In putting our improved device into use, 85 the frame having been covered with leather, as stated, the crupper is placed in position, the forward end covering being suitably attached to the saddle of the harness, and the breeching-strap passing through the slot in 90 the back-strap over the pointed end or apex of the frame, securely holding that end down between the horse's hips.

The cylindrical sleeve H fits under the root of the horse's tail, and the tail-support K fits 95 snugly to and under the stub of the tail. The hair of the tail is pushed aside and the straps or springs M passed around the stub within the hair and completely out of sight. The support K is now raised to give the tail the desired elevation, a pin or nail inserted in one 100 of the holes F in nut E, through slot J, and the

nut turned, which draws the threaded ends D of the rods B B toward each other and brings the serrations or ratchets on collars C C into engagement with the serrations or ratchets on the disks I I and locks them together, and thus securely holds the sleeve H and the tail-holder K in the desired position.

The sleeve H, being cylindrical, forms practically a continuation of the leather covering 10 of the side bars B and presents the appearance of an ordinary crupper, the adjusting and locking parts being concealed from view by said sleeve H. The support K, being concealed by the hair of the horse's tail, will also 15 be unobserved.

By means of the right and left threaded ends of rods B B, the right and left threaded nut, and the serrations or ratchets on the collars C C and the disks I I and concaved metal 20 tail-support K any desired curve or inclination may be given to the horse's tail and retained, thus adding to the appearance of the horse, especially in "showing" the animal, and also correcting the fault usual in most 25 horses of the tail hanging to one side. With this device the tendency of horses throwing the tail over the lines is obviated.

Having thus described our invention, what we claim as new, and desire to secure by Letters Patent, is—

1. A crupper, comprising a frame consisting of a front body portion and side bars extending rearwardly therefrom and bent toward each other at their rear ends but separated, a tail-holder frame pivotally mounted 35 on the separated rear ends of the side bars and bridging the opening between them, and means for adjustably securing said tail-holder to such separated rear ends of the side 40 bars.

2. A crupper comprising a frame consisting of side bars separated at their rear ends and having right and left threads thereon, shoulders adjacent to the ends of said rods, and 45 a tail-support consisting of hollow cylindrical portion fitting over the ends of said rods and a rearwardly-curved tail-supporting member, said cylindrical portion fitting between the shoulders on the rods, and a right and left 50 threaded nut engaging the threaded ends of the rods, whereby the said ends are adapted to be drawn toward each other and adjustably clamp the tail-holder between the shoul- dered portions of the rods.

3. A crupper comprising a frame consisting of side bars joined at their inner ends, and having their rear ends separated and oppositely threaded, collars rigidly secured to

said bars adjacent to their rear ends and provided with serrations or ratchets on their opposing faces, and a tail-support consisting of a cylindrical sleeve and a rearwardly-curved tail-support, said sleeve inclosing the threaded ends of said bars and provided with serrations or ratchets on its inner surface, and 60 a right and left threaded nut engaging the oppositely-threaded ends of the side bars, and fitting within the cylindrical sleeve, whereby the ends of the side bars may be drawn toward each other and the serrated faces of the 70 collars engage the serrations on the inner surface of the cylindrical sleeve, to adjustably secure and hold the tail-holder at any desired inclination.

4. A crupper comprising a frame consisting of side bars joined at their inner ends and a leather cover for the same, means for securing said frame to the horse's back, the rear ends of the said side bars being separated, and the leather cover forming shoulders adjacent to said rear ends, right and left threads on the ends of the side bars, collars rigidly secured to the side bars adjacent to the rear ends thereof and having serrations or ratchets on their opposing faces, a right 80 and left threaded nut engaging the oppositely-threaded ends of the bars and provided with sockets or holes in its periphery, and a tail-support consisting of a cylindrical sleeve surrounding said nut and a rearwardly-curved 85 concaved tail-holder projecting therefrom, said sleeve having a transverse slot, and serrations or ratchets on its inner surface adjacent to each end whereby when the nut is turned in one direction the rear ends of the 90 side bars will approach each other and the serrations on the collars and within the cylindrical sleeve engage each other, the ends of the sleeve abutting the shoulders formed by the ends of leather cover, and adjustably 95 secure the tail-holder at any desired inclination.

5. A crupper comprising side members whose rear ends converge but are separated, a tail-support held rotatably between said 100 rear ends, and means for forcing the side members toward each other and clamping the tail-support between the rear ends, whereby the tail-support may be adjusted and held at any vertical angle.
